UNITED STATES PATENT OFFICE.

JOHN H. EICKERSHOFF, OF CINCINNATI, OHIO.

OIL-SEPARATOR FOR STEAM-ENGINES.

SPECIFICATION forming part of Letters Patent No. 453,602, dated June 2, 1891.

Application filed September 19, 1890. Serial No. 365,569. (No model.)

To all whom it may concern:

Be it known that I, JOHN H. EICKERSHOFF, a citizen of the United States, residing at Cincinnati, Ohio, have invented new and useful 5 Improvements in Oil-Separators for Steam-Engines, of which the following is a specification.

My invention relates to an overflow-trap and oil-separator for use in connection with 10 crank-cases of steam-engines, or in other machinery where a body of water and oil is employed to lubricate parts by their movement intermittently therein.

To this end it consists in a double chamber 15 constructed and arranged as hereinafter set forth, connected with an outer overflow-cup, whereby the excess of water is trapped out without removing the oil.

Mechanism illustrating my invention is 20 shown in the accompanying drawings, in which—

Figure 1 is a cross-sectional elevation of a portion of a steam-engine crank-case to which 25 my invention is applied, showing the device in axial section; Fig. 2, a top view of the trap; Fig. 3, a plan section taken through the apertures of the outer and inner casings in the planes of each set of apertures; Fig. 4, a sectional view, corresponding with Fig. 1, of a 30 modification of the apparatus adapting it to be placed wholly outside of the crank-case; and Fig. 5, an enlarged section of Fig. 1.

Referring now to the drawings, A designates the crank-case of a common form of engine, having open-ended cylinders mounted 35 thereon, with their pitmen B extending into the crank-case attached in the usual manner to crank-wrists C. The lubrication in such cases is accomplished by floating a stratum 40 of oil on a body of water in the case into which the cranks dip in their rotation, thus splashing the oil and water over the interior parts. By leakage and condensation of steam, however, the body of water increases, thus 45 rendering necessary some means of trapping off the water. The constant agitation, however, causes the mingled liquids to assume somewhat the character of an emulsion and renders the removal of the water difficult 50 without also removing the oil.

To effect the separation of the oil and water, I employ a trapping-vessel constructed in

the preferred form. The trap consists of an elongated cylindrical casing F, which may be projected through the bottom of the crank-case A and held thereto by a peripheral flange a at about mid-length of the casing. The casing F is closed at the bottom and provided with a somewhat conical top f, having a central opening b and a marginal annular opening or series of openings c. A horizontal conical diaphragm d is placed centrally in the casing F, substantially similar to the top f, having central and marginal openings, and the casing F is laterally pierced with a series 60 of openings z just above the diaphragm d. The upper part of the casing F is surrounded by an outer casing E, resting upon the flange a and extending to near the top of the inner casing, to which it is held by radial lugs e and 70 screws, leaving an annular-space chamber between the casings, open above and communicating below with the crank-case by radial apertures g. A pipe G is passed downward through the central opening of the diaphragm d (leaving an annular space through the diaphragm around the pipe) to near the bottom of the inner casing. Above the diaphragm the pipe carries a peripheral flange h, of diameter somewhat smaller than the interior of the casing F, and thence connects 75 outwardly by the pipe G' with an open-sight overflow-vessel H, arranged exteriorly to the crank-case.

The main object of the construction is to 85 inclose a body of liquid as free from disturbing influences as possible, thus giving time and opportunity for the separation of oil and water to be effected by difference of specific gravity. Thus the combined oil and water 90 passing the outer casing through the apertures g enters the annular space between the casings, and, being somewhat protected from disturbing influences, the separation of oil and water begins, the oil rising directly upward and the water and remaining oil passing through the apertures z into the inner casing F, where the disturbing influences are 95 still less effective. Here a further separation takes place, the oil rising and the water and 100 trace of remaining oil passing downward through the marginal openings o of the diaphragm d. In the lower chamber of the casing F the final separation is effected, the oil

passing upward through the central opening of the diaphragm *d* around the pipe *G* and the water passing downward and finally upward and outward through the pipe *G* into the overflow-vessel *H*. The purpose of the outer vessel *H* is to give a visual indication at all times of the height of liquid in the crank-case. The ledge or flange *h* of the pipe *G* merely aids in protecting the body of liquid in the lower casing from agitating-currents, but may be omitted.

In the modification shown in Fig. 4 the trap is secured wholly at the outside of the crank-case. In this the outer casing *F* is a complete cylindrical box, having a cover *h'* and entered at one side midway by a pipe *i* and at the top by a pipe *j*, both extending into the crank-case. Within the crank-case a shield or screen *K* is preferably arranged beyond the mouth of the pipe *j*, as shown.

Within the casing *F* the inner casing *E* is provided as a mere annular partition pierced with radial holes at the bottom and entirely open at the top into the outer casing. The pipe *G* in this case extends from near the bottom of the inner casing centrally outward through the top and enters the overflow-vessel *H*. The action of the trap is substantially similar, the oil and water passing downward through the pipe *i*, the trapped oil passing back through pipe *j*, and the water passing through pipe *G* to the overflow-vessel *H*.

If by any accident the water falls too low in the crank-case, the fact is at once disclosed by the open vessel *H*, and it may be replenished by pouring in said vessel.

I claim as my invention and desire to secure by Letters Patent of the United States—

1. In combination with an engine crank-case wherein is maintained a body of oil and water for lubrication, an oil-separating trap embodying two or more chambers communicating in series and with the crank-case, the ultimate chamber having communication with the crank-case only through its upper portion

and provided with an overflow pipe or passage leading outward from its lower portion, substantially as set forth.

2. In combination with an engine crank-case wherein is maintained a body of oil and water for lubrication, an oil-separating trap embodying two or more concentric chambers communicating in series and with the crank-case, the inner chamber opening into the crank-case only at its upper portion, opening into its next outer chamber at or near the bottom of the latter, and opening outward independently beyond the crank-case from its lower portion by an overflow pipe or passage, substantially as set forth.

3. In combination with an engine crank-case wherein is maintained a body of water and oil for lubrication, an oil-separating trap consisting of a series of separating-chambers communicating in series and with the crank-case, a pipe or passage leading outward from the bottom of the ultimate chamber in series, and an overflow-vessel outside of the crank-case with which said pipe communicates, whereby the height of liquid in the case may be at all times ascertained and regulated, substantially as set forth.

4. An oil-separating trap embodying substantially a vertically-extended chamber having a perforated top, an intermediate perforated partition above its closed bottom, a concentric outer casing forming an open annular chamber communicating with the inner chamber above the intermediate perforated diaphragm, and an overflow pipe or passage leading outward from the lower portion of the inner chamber, substantially as set forth.

In testimony whereof I have hereunto set my hand in the presence of two subscribing witnesses.

JOHN H. EICKERSHOFF.

Witnesses:

L. M. HOSEA,
HENRY APPLETON.
